UNITED STATES PATENT OFFICE.

FREDERICK S. WOODWARD, OF RICHMOND HILL, NEW YORK.

ELECTROLYTIC PROCESS.

1,374,541.

Specification of Letters Patent. Patented Apr. 12, 1921.

No Drawing.

Application filed July 25, 1919. Serial No. 313,329.

To all whom it may concern:

Be it known that I, FREDERICK S. WOODWARD, a citizen of the United States, and a resident of Richmond Hill, Long Island, 5 New York, have invented a new and useful Electrolytic Process, of which the following is a specification.

My invention relates to electro-depositions of metals for plating operations or for 10 production of pure metals electrolytically, and is especially applicable to copper deposition. The object of the invention is to avoid the necessity of using as anodes the material which is to be deposited, thus being 15 able to secure the desired metal indirectly from cheaper sources of supply.

According to my invention I plate or deposit the copper from an electrolytic bath originally made up, for example, of an 20 aqueous solution of copper sulfate and free sulfuric acid. Insoluble anodes are employed, such as lead, or other suitable material not soluble in the bath. The use of 25 insoluble anodes results in rapid depletion of the copper content of the bath, as copper is deposited from the copper sulfate solution and free sulfuric acid is produced as a result. This free sulfuric acid tends of course to increase as the copper content diminishes. The invention therefore proved 30 a regenerating or rejuvenating process for maintaining the proper proportions of copper sulfate and free acid in the bath.

This rejuvenating of the sulfate solution 35 may be accomplished in various ways. The addition of copper sulfate directly to the depleted solution would not avoid the continued increase of free sulfuric acid, and therefore according to my invention the rejuvenation includes at the same time the 40 provision of a neutralizing action for the increment of free sulfuric acid arising in the depositing operation. This may be accomplished for example by the introduction 45 of copper sulfate and a base or salt capable of forming an insoluble sulfate without contaminating the solution. Examples of such bases or salts are calcium oxide and calcium carbonate. Instead of adding 50 copper sulfate and a separate base or salt for precipitating the insoluble sulfate, I may neutralize the increment of free sulfuric acid by a copper compound capable of reacting therewith to produce within the

bath additional quantities of copper sulfate. 55 Examples of such compounds would be oxides and carbonates of copper. In the selection of suitable copper compounds care is taken that undesirable soluble by-products are avoided. In the use of copper oxide for 60 example, the setting free of another acid radical is avoided, whereas carbonates are advantageous as the resulting acid radical set free is gaseous and does not remain in solution to contaminate the bath. This 65 added substance may be relatively cheap and need not be particularly pure. Minerals such as malachite and azurite are suitable.

Where an insoluble sulfate is produced 70 from the excess of free sulfuric acid suitable procedure is followed to remove this from the bath before returning the bath to the depositing operation. Calcium sulfate for example may be settled out or filtered 75 from the solution. The small solubility of this salt would avoid objectionable quantities being retained as once the solution is saturated for calcium sulfate no further quantity would be dissolved. 80

I claim:

1. An electrolytic process comprising depositing copper from an acid bath with an anode insoluble in the bath, and neutralizing only the resulting increment of free 85 acid while restoring the bath to normal strength and condition.

2. An electrolytic process comprising depositing copper from an acid bath with an anode insoluble in the bath, removing the 90 depleted bath, introducing into the depleted bath chemical substance capable of and in amount suitable for neutralizing only the resulting increment of free acid and restoring the strength and constitution of the bath 95 to normal, and returning the bath to again serve in the deposition of metal.

3. An electrolytic process comprising depositing copper from acid solution of copper sulfate in water, with the use of an insoluble anode, withdrawing the spent solution from the depositing operation, treating the spent bath chemically to restore the copper sulfate to normal strength and neutralize only the increment of free sulfuric acid, 105 and returning the restored bath for further deposition of metal.

FREDERICK S. WOODWARD.
